UNITED STATES PATENT OFFICE.

THOMAS COULTAS AND THOMAS I. COULTAS, OF PITTSBURGH, PENNSYLVANIA.

HOT-BLAST STOVE.

1,161,031.

Specification of Letters Patent. Patented Nov. 23, 1915.

Application filed March 9, 1914. Serial No. 823,385.

To all whom it may concern:

Be it known that we, THOMAS COULTAS and THOMAS I. COULTAS, citizens of the United States, residing at Pittsburgh, in the county of Allegheny and State of Pennsylvania, have invented new and useful Improvements in Hot-Blast Stoves, of which the following is a specification.

The invention relates to hot blast stoves of the "three pass" type, as are employed in heating the blast used in blast furnaces.

Among others to be hereinafter brought out, a particular object of the invention is to so improve the construction of blast stoves as to increase the life, improve the operation, and facilitate and cheapen the construction and repair thereof.

To enable others skilled in the art to which this invention appertains to construct and use the improved stove for blast furnaces, reference will be had to the accompanying drawings forming a part of this specification and wherein like characters of reference are used to designate corresponding parts throughout the several views, in which:—

Figure 1 is a vertical sectional view; Fig. 2 is a cross sectional view therethrough on the line 2—2, 3—3; and Fig. 3 is an enlarged vertical sectional view of an upper fragment of the invention.

The invention comprises the central well-hole formed by the circular sub-well wall 1 and the well wall B, the latter being known as the B-wall and being concentric with the sub-well wall, and extended therabove. Concentric with the well-walls, is an outer circular wall A known as the A-wall, and between the A-wall, and the well wall B, and concentric therewith is a wall C, known as the C-wall. The well-walls and the A-walls are built upon the stove foundation, and the C-wall rests upon radial arch walls 2 and arch blocks 3', the latter bridging the spaces between the arch walls 2 as in Patent No. 1,057,940. These three principal walls provide the three passes for the blast and gas, the well-hole constituting one pass, the space between the well wall B and the C-wall another, and the space between the C-wall and the A-wall the third pass. Within the pass between the well-wall B, and the C-wall, and completely independent of bond therewith is provided the checker-work which stands as a unitary structure capable of movement under ex-

pansion and contraction due to the alternate heating and cooling effects, and such movement being entirely independent of the unrelated movements from the same causes, of 60 the well and C-walls.

The checker-work includes skin-walls 5 and 6, respectively built against and free of bond with, the B and C-walls. At regularly spaced intervals between these skin walls, are provided with-walls 7, 8 and 8; all of said walls 5 to 9 inclusive being circular and concentrically related. The spaces between the skin and with-walls are divided by radial blocks and walls, as will be 70 more specifically described, thereby dividing the second pass, or that pass between the B and C-walls into numerous small flues.

The partitions to be later specifically described, which divide the outer pass into 75 numerous small flues, is bonded with the A-wall and engage with, though entirely free of bond with the C-wall.

The entire stove is incased in a metallic shell comprising the cylindrical body section S and the dome section S', suitably connected together. To the upper end of the shell section S and interiorly thereof is riveted, or otherwise secured, a metallic ring 10 formed from an L-angle iron co-incident 80 with which is the upper termination of the A-wall. A skew-ring 11 of refractory material rests upon the angle iron 10 within the channel thereof, and upon the inner beveled edge of the skew-ring is built the 85 outer dome 14, supporting the stack wall 15. The upper face of the dome 14 alines with the upper edge of the angle ring 11, and as the shell section S extends slightly above the angle ring to support the dome 90 shell S', a space is provided between the dome shell S' and the refractory dome 14 which space is filled with loam or cinders 95 15' permitting a limited amount of lateral expansion to the dome 14. Thus it will be 100 observed that the outer dome is supported entirely independently of the A-wall, whereby one or the other (dome or A wall) may be constructed or repaired regardless of the presence or absence of the other. 105

The upper end of the C-wall is provided with a skew-ring 16 which supports the refractory inner dome 17. In its expansion, this dome produces lateral pressure upon the C and A-walls, which pressure is resisted by the steel shell S, and an insert of 110 splits 18 located between the shell S and

A wall. The splits occur as a refractory lining confined entirely to the hot zone of the stove, being arranged in courses as illustrated in Fig. 3. The upper portion or that portion of the shell S located within the hot zone of the furnace is increased in thickness as indicated by numeral 19 in Fig. 1. Below the hot zone the space between the shell S and A-wall is packed with loam or cinders 20 to permit lateral expansion of the A-wall. The cinder packing 20 terminates at a point substantially adjacent the lower end of the C-wall where a few courses of splits 21 fill the bottom of the space between the shell S and A wall.

In Fig. 2 is illustrated the construction of the various courses 2 and 3, one course alternating with the other throughout the structure. In course 2, the well wall A is composed of two superposed layers of bricks 22 and 23; the skin walls 5 and 6 of bricks 24, 25 respectively; the circular with walls of brick 26, 27 and 28; the A-wall of two horizontally parallel layers of bricks 29, 30; and the C-wall of bricks 31. In course 3, the well wall A is composed of two superposed layers of bricks 32, 33; the skin walls 5 and 6 of bricks 34, 35 respectively; the circular with walls of bricks 36, 37 and 38; the A-wall of two superposed layers of bricks 39, 40; and the C-wall of bricks 41. In both courses, radial with walls divide the passages between the skin walls 5 and 6 and the circular with walls into numerous small flues. In course 2, the radial with walls 42 and 43 of bricks set end to end are provided and in course 3 the radial withes 44 and 45 are provided for the same purpose. The radial with walls 42 and 43 abut the C-walls and pass through the skin wall 6 and the circular with walls 7 and 8. The radial with wall 42 abuts the circular with wall 9 and the radial with walls 43 pass through the circular with wall 9 and skin wall 5 and abut the well wall B. Neither of the radial with walls 42 nor 43 bonds with the C or well walls. To prevent the bricks of the skin wall from becoming dislodged, due to expansion, contraction or warping, they are, in course 2, beveled at their ends 46 to receive the tapered ends 47 of the radial with walls 43.

In course 3, neither of the radial with walls 44 nor 45, passes through the circular with or skin walls, but the construction is to the contrary, the withes being respectively in radial series, but merely placed between the several walls, and withes 45 being absent between the skin wall 5 and circular with wall 9.

The passage between the A and C-walls is likewise divided into small flues by withes 50 and 51 respectively in the two courses. The withes 50 of course 2 merely abut withes 50 out bond with the C wall and layer 29 of

the A-wall, but pass through the layer 30 of the A-wall and hence have bond with the A-wall alone. The withes 51 of course 3 have bond with neither of the walls A and C, being merely inserted between the two. The radial bricks 50 aline with the radial with walls 42 and 43 and those 51 with the withes 44 and 45, and all bricks of one course aline vertically with the corresponding bricks of the next course, hence each course corresponds with and is supported by or supports the next adjacent course throughout the structures.

In practice, the effect of the alternate heating by the gas and cooling by the blast with the incident severe vibration, results in warping, chipping, settling and other injurious effects upon the bricks and walls individually and collectively, and it is to prevent this as much as possible and when not so to make the repair as easy and inexpensive as possible without necessitating razing of the major portion of the structure. It has been found with the usual stoves of this type that the A-wall, which is intended to be and should be the most permanent vertical wall of the entire structure and should last the lifetime of the structure, in due course of time materially settles, thereby letting down bodily the upper or outer dome 14 and in some instances permitting said dome to cave in. To obviate this, the dome supporting ring 10 of this invention is provided whereby the dome is supported independently of the A-wall and at the same time the A-wall is permitted its independent movement in expanding and contracting or settling, and further is permitted to be repaired without necessitating razing of the dome 14.

In the event of the well-wall B becoming deranged from any cause, it may be readily repaired without disturbing the checker-work or any other wall of the structure, as it stands alone as a unitary structure capable of its own peculiar movements in expanding and contracting or otherwise.

The checker-work, which likewise stands as a unitary mass free from bond with the well wall B or the C-wall, may expand or contract freely and unrelatedly to the movements of said walls B and C. When the checker-work is to be repaired, it may be torn out without derangement of the B or C-walls, and may be rebuilt as in the initial construction.

In case the C-wall becomes disorganized or otherwise in need of repair, it may be repaired or rebuilt without disturbance of the standing A-wall, though, as in all stoves of this type, requiring a portion of the checker-work being removed to permit access to said C-wall.

It will be noted that the severe actions of the several agencies upon the vertical walls of these stoves is such as to frequently occa-

sion what is known as "short circuiting" of the passes. If a brick in any of the vertical walls becomes disintegrated or dislodged, the gas or blast currents instead of taking the 5 prescribed course through the several passes and flues, cuts through the aperture formerly occupied by the dislodged brick, thereby destroying the effectiveness and in all cases necessitating immediate repair. Thus the 10 item of repair with its incident expense and consummation of time, becomes as important a factor as the item of initial construction and effectiveness in operation.

What is claimed is:

- 15 1. In a hot blast stove, a well-wall, a second wall spaced therefrom and forming a pass therebetween, and a third wall spaced from the second and forming a pass therebetween, checker-work dividing the pass between the well and second walls into flues 20 and comprising a unitary mass free from bond with the said walls, and checker-work dividing the pass between the second and third walls into flues and being bonded with the third wall and free from bond with the 25 second wall.
2. In a hot blast stove, a well-wall, a second wall spaced therefrom, a unitary body of checker-work therebetween, a third wall spaced from the second wall, checker-work bonded with and forming a unit with the third wall and being free from bond with

the second wall, a dome forming a continuation of the third wall, said well wall, checker work, second wall, and third wall being free 35 from bond with each other and movable under expansion and contraction independently of each other, and the dome being supported independently of all of the said walls.

3. In a hot blast stove, a shell, an outer wall inclosed thereby, an inner wall inclosed by the outer wall, said outer wall being spaced from the shell and inner wall and movable under expansion and contraction independently thereof, said space being partially filled with a yielding material, checker-work bonded with the outer wall and free from bond with the inner wall, a dome on the inner wall causing outward pressure to be exerted on the outer wall, and a relatively non-yielding material filling the remainder of said space and being located to resist said outward pressure, and an outer dome supported independently of said outer wall.

In testimony whereof we have hereunto set out hands in presence of two subscribing witnesses.
